UNITED STATES PATENT OFFICE.

GEORGE S. PARKER, OF SALEM, MASSACHUSETTS.

DESIGN FOR A GAME-BOARD.

SPECIFICATION forming part of Design No. 28,904, dated June 21, 1898.

Application filed May 9, 1898. Serial No. 630,222. Term of patent 14 years.

To all whom it may concern:

Be it known that I, GEORGE S. PARKER, of Salem, in the county of Essex and State of Massachusetts, have invented and produced 5 a new and original Design for Game-Boards, of which the following description, in connection with the accompanying drawing, is a specification, like letters on the drawing representing like parts.

10 The drawing is a plan view of a game-board embodying the design.

The leading feature of the design consists in the pictorial representation upon the board 15 a of groups or blocks of buildings b , between which are a series of open spaces b^2 , whereby the said groups are mainly separated from each other. The said spaces are each subdi-

vided by lines or marks b^3 , arranged along the same between the groups to afford units of travel in playing the game.

20 The design further embodies pictorial representations of wharves, ships, &c., also indicating parks, water front, and other physical characteristics, as shown in the drawing.

I claim—

25 The design for a game-board substantially as herein shown and described.

In testimony whereof I have signed my name to this specification in the presence of two subscribing witnesses.

GEORGE S. PARKER.
